(Cl. D56—4)

FIG. 1

FIG. 3

FIG. 2

FIG. 4

FIG. 5

FIG. 6

FIG. 1 is a front perspective view of a portable television receiver, showing my new design;

FIG. 2 is a right side elevational view, to a reduced scale;

FIG. 3 is a left side elevational view, on the same scale as FIG. 2;

FIG. 4 is a front elevational view, to an enlarged scale;

FIG. 5 is a rear perspective view, to a reduced scale; and

FIG. 6 is a top plan view thereof, slightly enlarged with respect to FIG. 1.

The dominant features of my design reside in those portions of the drawings shown by means of full lines.

I claim:

The ornamental design for a portable television receiver, substantially as shown and described.
